UNITED STATES PATENT OFFICE.

CYRIL H. MAY, OF IRONWOOD, MICHIGAN.

KEYHOLE-FINDER.

1,384,622.

Specification of Letters Patent. Patented July 12, 1921.

Application filed May 13, 1920. Serial No. 381,120.

To all whom it may concern:

Be it known that CYRIL H. MAY, a citizen of the United States, residing at Ironwood, in the county of Gogebic and State 5 of Michigan, has invented certain new and useful Improvements in Keyhole-Finders, of which the following is a specification.

This invention relates to a key hole finder for door locks. The object of the invention 10 is to facilitate the location of a key hole when attempting to insert a key to manipulate the lock for opening the door.

Figure 1 is a view showing the escutcheon plate of a door lock depressed to form a 15 guide for the key.

Fig. 2 is a front view showing a depressed plate which is adapted to be attached to any lock for effecting the same result.

Fig. 3 is a vertical, transverse, sectional view showing the key hole finder in the form 20 of an adjustment, and

Fig. 4 is a view showing a modified form of fastening means for adapting the key hole finder to the lock.

25 A, indicates a door which is provided with the usual lock B. As illustrated in Fig. 1, the escutcheon plate 1, is depressed as at 2, thereby providing an inclined surface directed toward the key hole 3, whereby 30 the user when attempting to insert a key in the key hole is assisted materially in locating the latter.

As disclosed in Figs. 2 and 3, the invention 35 may be incorporated in the form of an adjustment comprising a plate 4, provided with an annular flange 5, of sufficient height to permit the plate to be depressed as at 6, the depression being inclined toward an opening 7, similar in shape to the opening 3, 40 in the escutcheon plate 1, of the lock. As a means for fastening this plate to the door I preferably provide the plate 4, with inwardly projecting lugs 11-11 which are adapted to extend inwardly from the upper 45 and lower edges of the opening 7, in the finder plate and are of such a length as to be bent outwardly after passing through the opening or key hole in the escutcheon plate

thereby securely fastening the plate to the lock. To adapt the plate 4, to different size 50 openings in the escutcheon plate, parallel slots 12-12 are provided on either side of the lower lug 11, permitting the opening 7, to be made longer where occasion requires.

If desirable a fastening means as disclosed 55 in Fig. 4, may be employed wherein the lower end of the finder plate 4, is extended somewhat beyond the escutcheon plate and a screw 13, is passed through an opening therein, the screw then passing through a 60 small spiral spring 14, thence into the wood of the door and tightened up to bring the finder plate 4, flush with the escutcheon plate after which a screw 15, is passed through 65 both plates tightly holding them in place, the lugs 11-11 in this instance merely acting as guides to properly locate the finder with respect to the key hole opening in the escutcheon plate.

From the above it is apparent I have devised a key hole finder which may be applied to any form of lock without the necessity of removing any screws or the use of any additional screws to deface or otherwise mar the door.

75 I claim:

1. A combination of an escutcheon plate provided with an opening, a finder plate provided with an opening, an inclined depressed portion surrounding said opening 80 and lugs extending inwardly from the opening adapted to be received in the opening of the escutcheon plate whereby the two are fastened together.

2. A combination of an escutcheon plate 85 provided with an opening, a flanged plate provided with an opening adapted to register with the opening in the escutcheon plate, and an inclined depressed portion surrounding the opening in the finder plate and 90 lugs extending inwardly from the finder plate adapted to be received in the opening in the escutcheon plate whereby the two are secured together.

In testimony whereof I affix my signature. 95
CYRIL H. MAY.
